CLAIM

The ornamental design for the wide power pole, as shown and described.

DESCRIPTION

FIG. 1 is a front view of a wide power pole according to an embodiment of the present invention;

FIG. 2 is a bottom cross-sectional view of the power pole of FIG. 1;

FIG. 3 is a top cross-sectional view of the power pole of FIG. 1;

FIG. 4 is a left-side view of the power pole of FIG. 1;

FIG. 5 is a right-side view of the power pole in FIG. 1;

FIG. 6 is a rear view of the power pole of FIG. 1; and,

FIG. 7 is a front view of the power pole in FIG. 1 with an outlet cover in an open position.

The broken line showing is for illustrative purposes only and forms no part of the claimed design.
